SHIP CONSTRUCTION

Lawrence Y. Spear, New London, Conn., assignor
to Electric Boat Company, Groton, Conn., a
corporation of New Jersey

Application February 23, 1932, Serial No. 594,442

12 Claims. (Cl. 114—2)

This invention relates to ship construction, and has to do more particularly with armored warships.

One of the main objects of my invention is to provide means whereby all of the guns of the main battery of a war-ship may be fired either directly forward or directly astern, as well as at intermediate positions, thus materially increasing the efficiency of the ship for combatant purposes. More specifically, my invention has to do with a novel arrangement and relation of the bridge and gun turrets, the bridge being disposed to clear the guns and to be out of the line of fire thereof in any firing position of the guns, the turrets being rotatable for positioning the guns to fire either forwardly or astern. A further object of my invention is to provide an improved means for giving access to the conning tower from the interior of the hull, such means acting to shield the means of communication and control as well as the personnel when passing from the interior of the ship to the conning tower, and vice versa. It is also an object of my invention to provide means for projecting depth bombs or the like beyond the sides of the ship, this projecting means, when in use, being disposed below the line of fire of the guns of the main battery when such guns are disposed at minimum elevation. Further objects and advantages of my invention will appear from the detail description.

In the drawings:—

Figure 1 is an outboard profile view of a war ship constructed in accordance with my invention;

Figure 2 is a plan view of the midship portion of the main deck and of the bridge and gun turrets and associated parts;

Figure 3 is a plan view of the stern portion of the berth deck;

Figures 4 and 4A, taken together, form a sectional view of the ship taken substantially along the keel line;

Figure 5 is a fragmentary outboard profile view of the ship illustrating a modified form of bridge and turret construction in accordance with my invention;

Figure 6 is a plan view of the midship portion of the main deck and the bridge and turrets of Figure 5;

Figure 7 is a fragmentary outboard profile view of the ship illustrating a second modified form of bridge and turret construction;

Figure 8 is a section taken substantially on line 8—8 of Figure 9;

Figure 9 is a section taken substantially on line 9—9 of Figure 8;

Figure 10 is a section taken substantially on line 10—10 of Figure 8;

Figure 11 is a section taken substantially on line 11—11 of Figure 4A.

I have illustrated my invention as applied to a war-ship having a hull 1 which is, in general, of known construction. The interior of this hull is separated, in a known manner, into various rooms, compartments, tanks and storage spaces. In the drawings, the ship is illustrated semi-diagrammatically, in great part, the propelling engines, steering engines and various other mechanisms being omitted for clearness of illustration.

The ship is provided with an upper main deck 2, a berth deck 3, and an armored deck 4, and, in addition, in the central portion in wake of the belt armor, a splinter deck 4b is provided, which is horizontal over the magazine, shell rooms and handling rooms, and inclined at 4c in wake of the engine room. The midship portion of the armored deck extends substantially parallel with the midship portion of the main deck. The end portions of the armored deck are inclined downwardly toward the stern and the bow, and also downwardly to the sides as at 4a. The belt of armor 5 extends along each side of the hull, at the midship portion thereof, and downwardly from the armored or protective deck 4. The midship portion of the hull is thus protected by the armored deck 4 and the armor belts 5, and the vitals of the ship, such as the battle control station, battle dressing station, radio room, magazines, handling rooms and engines are all located in this central armored portion of the hull. The magazines and handling rooms are given additional protection by the horizontal splinter deck 4b, and the engine rooms by the inclined splinter deck 4c. At the stern is provided an armored compartment 6, for the steering engine (not shown).

At the after portion of the berth deck 3 there is provided a storage room 7 for mines 8, or depth charges, or both, which may be ranged along the sides of the room as in Figure 3. A mine and/or depth charge discharge tube 9 opens through the stern of the hull for discharging mines and/or depth charges therefrom, suitable conveying means 10 being provided for delivering the mines and/or depth charges to this tube. I also provide, at the forward end of room 7, a depth charge projector 11, for projecting depth bombs or the like over the sides of the main deck 2. A suitable hatch 12 is provided through the main

deck, above the gun 11, to permit of discharge of bombs from the latter. The hull is provided with suitable door openings, hatches, passages and companionways giving access to the various rooms 5 and compartments, and the hatches opening through the main deck are sufficiently low to in no way interfere with fire of the guns of the main battery, as will be hereinafter more fully described. It is also to be noted that the depth 10 charge projector, when in use, is disposed below the line of fire of the guns of the main battery when such guns are disposed at minimum elevation.

At approximately the center of the midship 15 portion of the main deck 2 I provide a superstructure 13, two decks high, the upper part of which is used for a navigating station, and the lower part for deck offices, an entrance enclosure, etc. A bridge 14 is supported by this superstructure, 20 this bridge comprising a main or body portion 15 of approximately elliptical shape, which extends diagonally of the deck and substantially fore and aft thereof, and laterally projecting terminal portions 16. An armored tube 17 extends through 25 the center of bridge 14 and downwardly through the superstructure 13 and deck 2, this tube extending to the armored deck 4. A conning tower 18 is suitably supported on the upper end of tube 17 in communication therewith and centrally of 30 the bridge, and supports a mast 18a provided with a spotting station 19, a search-light platform 20 and a gun top 21. Anti-aircraft guns 22 are suitably mounted upon the gun top 21 and the bridge 14. The armored tube 17, and the mast, 35 may conveniently be provided with suitably disposed doorways or openings and doors therefor. The tube 17 gives access, from the interior of the hull, to the conning-tower, bridge and mast, and vice versa, while providing effective protection for 40 the personnel, and means for communication and control.

Two gun turrets 23 are disposed on the main deck at opposite sides of the superstructure 13, one of these turrets being forward of the superstructure and the other turret being astern of the superstructure. The terminal portions 16 of the bridge extend over the turrets 23 and are disposed an appreciable distance above the same. The turrets are of known construction and are 45 suitably mounted on barbettes 24 for turning movement on vertical axes, the axes about which the respective turrets turn being indicated by the lines *a*—*a* in Figure 1. Guns 23a are suitably mounted within the turrets for turning movement therewith, these guns being adjustable in a known manner and having a maximum elevation of approximately 35 degrees while being capable of being depressed approximately 5 degrees. The tops of the turrets 23 are unobstructed and 50 are available for mounting guns or instruments thereon, such as range finders 25.

Referring more particularly to Figure 2, it will be noted that the axis of the armored tube 17, which coincides with the center of the bridge 14, 55 intersects the line *x*—*x* connecting the axes of rotation *a* of the turrets 23, the axis *b* of the armored tube, which is also the axis of the mast, being equidistant from the axes *a* of the turrets. The bridge and the turrets are thus disposed in 60 echelon, with the body portion of the bridge between the turrets and extending approximately fore and aft of the main deck 2. This relation between the bridge and the turrets permits of the turrets being turned through an arc of approximately 317 degrees, as indicated in Figure 2, it

being noted that the bridge is supported above the turrets in position to clear the guns thereof and out of the line of fire of the guns in any firing position of the latter. This renders it possible to fire all of the guns of the main battery either directly forward or directly astern, or to fire all of the guns of the main battery either forward or astern or over either side of the ship. The combatant efficiency of the ship is thus greatly increased over ships in which all of the 10 guns of the main battery cannot be fired both forward and astern, as above described. The disposition of the depth charge projector 11 below the line of fire of the guns 23a, when the latter are at minimum elevation, is advantageous as 15 avoiding interference with firing of the guns of the main battery astern.

In the modified form illustrated in Figures 5 and 6, I provide a bridge 26 comprising a central approximately circular portion 27, rectangular end portions 28 and elongated rectangular portions 29 connecting the center and end portions. This bridge is disposed diagonally of the main deck and is supported, at each end, by a column 30 extending from turret 23, the end portions 28 of the bridge being supported by pivot bearings 31 of suitable type, at the upper ends of the columns, the axes of the columns coinciding with the axes on which the turrets turn. The central portion of the bridge is supported by a tubular 30 supporting structure, in the nature of a superstructure, extending upwardly from the main deck. Armored tube 17 passes upwardly through the supporting structure 32 and has associated therewith the conning tower 18 and the tubular 35 mast 18a, as in the construction illustrated in Figures 1 to 4, inclusive, and above described. Since the supporting structure 32 is of less extent diagonally of the main deck than the superstructure 13 of Figure 1, the arc through which the guns may be turned is correspondingly increased, 40 this arc being approximately 319 degrees.

In both forms of my invention illustrated and above described, it is possible to secure maximum angle of fire from all of the guns of the main battery and provision is made for firing all of such guns directly ahead and directly astern, as well as at intermediate positions, both astern and ahead, and over either side, thus rendering the ship highly efficient for combatant 45 purposes. In the form illustrated in Figures 5 and 6, the bridge is disposed above the turrets and in position to clear the guns and out of the line of fire thereof in any firing position of the guns. Also, in both forms illustrated and described, the 50 deck is clear of all obstructions to firing of the guns.

The modified form illustrated in Figure 7 is similar to that of Figures 5 and 6, with the exception that the supporting column 30a at each 55 end of the bridge is carried by the bridge and has a suitable pivotal mounting at its lower end, at 33, on the underlying gun turret 23.

As above indicated, and as will be understood by those skilled in the art, changes in construction and arrangement of parts of my invention may be resorted to without departing from the field and scope of the same, and I intend to include all such variations, as fall within the scope of the appended claims, in this application in 60 which the preferred forms only of my invention are disclosed.

What I claim is:—

1. In combination in a war-ship having a main deck, a supporting structure extending upwardly 75

- from the deck, two gun turrets and guns therein on the main deck and at opposite sides of said structure, the turrets being rotatable to bring the guns into position to fire either forward or astern, 5 and a bridge supported by the supporting structure above the turrets, the bridge comprising a main portion extending diagonally of the deck and terminal portions extending laterally over the turrets, said bridge being disposed to clear 10 the guns and out of the line of fire thereof in either firing position of said guns.
2. In combination in a war-ship having a main deck, a bridge extending diagonally of the deck, and gun turrets and guns therein on the deck 15 and adjacent the ends of the bridge, the turrets being rotatable to position the guns to fire either directly forward or astern or forward or astern over either side of the deck, the end portions of the bridge overlying the turrets and being disposed above the turrets and the guns and to clear the guns and out of the line of fire thereof in any firing position of said guns.
3. In combination in a war-ship having a main deck, two gun turrets and guns therein on the 25 main deck, said turrets being rotatable to position the guns to fire either directly forward or directly astern, and a bridge supported above and overlying the turrets and the guns and disposed to clear the guns and out of the line of fire thereof in either of said positions of said guns, the bridge and the turrets being arranged in echelon with each other.
4. In combination in a war-ship having a main deck, two gun turrets and guns therein on the 35 main deck, said turrets being rotatable to position the guns to fire either directly forward or directly astern, and a bridge supported above and overlying the turrets and the guns and disposed to clear the guns and out of the line of fire thereof in either of said positions of said guns, the bridge and the turrets being arranged in echelon with each other with the center of the bridge on the line connecting the axes of rotation of the turrets.
5. In combination in a war-ship having a main deck, two gun turrets and guns therein on the main deck, said turrets being rotatable to position the guns to fire either directly forward or directly astern, a superstructure extending above the deck and disposed between the turrets, the superstructure and the turrets being arranged in echelon with each other with the axis of the superstructure on the line connecting the axes of rotation of the turrets, and 55 a bridge supported by the superstructure above and overlying the turrets and the guns and disposed to clear the guns and out of the line of fire thereof in either position of said guns.
6. In combination in a war-ship having a main deck, two gun turrets and guns therein on the main deck, said turrets being rotatable to position the guns to fire either directly forward or directly astern, a superstructure extending above the deck and disposed between the turrets, the superstructure and the turrets being arranged in echelon with each other with the axis of the superstructure on the line connecting the axes of rotation of the turrets, a bridge supported by the superstructure above and overlying the turrets and disposed to clear the guns and out of the line of fire thereof in either position of said guns, an armored tube extending upwardly through the superstructure, a conning tower at the upper end of the tube, and a tubular 70 mast extending upwardly from said conning tower.
7. In combination in a war-ship having a main deck, a bridge extending substantially diagonally of the deck, gun turrets and guns therein on the deck adjacent the ends of the bridge, said turrets being rotatable to position the guns to fire either forward or astern, and means for supporting the bridge from and above the turrets, said bridge being disposed to clear the guns and out 10 of the line of fire thereof in either position of said guns.
8. In combination in a war-ship having a main deck, a bridge extending diagonally of the deck, gun turrets and guns therein on the deck adjacent the ends of the bridge, said turrets being rotatable to position the guns to fire either forward or astern, said bridge being disposed above the turrets in position to clear the guns and out of the line of fire thereof in either position of the guns, and means for projecting bombs over the sides of the deck, said means being disposed below the deck and said deck having a hatch opening disposed to accommodate the projecting means, said projecting means when in use being below the line of fire of the guns when the latter are at minimum elevation.
9. In combination in a war-ship having a main deck, a bridge extending substantially diagonally of the midship portion of the deck, gun turrets and guns therein on the deck adjacent the ends of the bridge, said turrets being rotatable to position the guns to fire either forward or astern, said bridge being disposed above the turrets in position to clear the guns and out of the line of fire thereof in either position of the guns, and means at the stern portion of the deck for projecting bombs over the sides of the deck, said means being disposed below the deck and said deck having a hatch opening disposed to accommodate the projecting means, said projecting means when in use being below the line of fire of the guns when the latter are at minimum elevation.
10. In combination in a war-ship comprising a hull divided into various compartments including an ammunition room, an upper armored deck, armor belts extending downwardly from said deck and along each side of the hull at the midship portion thereof, the vitals of the ship being disposed at the midship portion of the hull beneath said deck and between the armor belts, and a lower splinter deck underlying the midship portion of the armored deck and overlying the ammunition room and adjacent areas of the interior of the hull.
11. In combination in a war-ship comprising a hull divided into various compartments including engine and ammunition rooms, an upper armored deck, armor belts extending downwardly from said deck and along each side of the hull at the midship portion thereof, the vitals of the ship being disposed at the midship portion of the hull beneath said deck and between the armor belts, and a lower splinter deck underlying the midship portion of the armored deck and overlying the ammunition room and adjacent areas of the interior of the hull, said splinter deck including elements extending from the lower edges of the armor belts and at an upward and inward inclination over the sides of the engine room.
12. In combination in a warship having a main deck, a bridge extending across the deck, and two gun turrets and guns therein on said deck, one at one side and forward of the center of 75

the bridge and the other at the other side and astern of the center of the bridge, said turrets being rotatable into positions to dispose the guns to fire either directly forward or directly astern,
5 the end portions of the bridge overlying the turrets and being disposed above and to clear the

guns and out of the line of fire thereof in either of said positions of said guns, the deck being free of obstructions in the line of fire of the guns when the latter are disposed to fire either directly forward or directly astern.

LAWRENCE Y. SPEAR.
